(57) **CLAIM**

The ornamental design for a power controller and user interface housing, as shown and described.

DESCRIPTION

FIG. 1 is a top perspective view of the power controller and user interface housing showing my new design;

FIG. 2 is a top perspective view thereof;

FIG. 3 is a right side view thereof;

FIG. 4 is a back side view thereof;

FIG. 5 is a left side view thereof;

FIG. 6 is a front side view thereof; and,

FIG. 7 is a bottom view thereof.

The broken lines are included for the purpose of illustrating environmental structure and form no part of the claimed design.
